Filed July 29, 1968, Ser. No. 12,955

Claims priority, application Czechoslovakia Jan. 31, 1968

Term of patent 7 years

Int. Cl. D6—01

U.S. Cl. D33—7

FIG. 1

FIG. 2

FIG. 3

FIG. 4

FIG. 1 is a front perspective view of a desk for audio-visual teaching showing our design;

FIG. 2 is a top plan view of the desk;

FIG. 3 is a side elevational view taken from the left in FIG. 1; and

FIG. 4 is a side elevational view taken from the right in FIG. 1.

The back of the design is conventionally plain and unornamented.

We claim:

The ornamental design for a desk for audiovisual teaching, as shown and described.
